CLAIM

The ornamental design for a case for magnetic tape cassettes, as shown and described.

DESCRIPTION

FIG. 1 is a perspective view of a case for magnetic tape cassettes, showing my new design;

FIG. 2 is a front elevational view thereof;

FIG. 3 is a right side elevation view, the left side being a mirror image thereof;

FIG. 4 is a rear elevational view thereof;

FIG. 5 is a top plan view thereof; and

FIG. 6 is a bottom plan view thereof.

FIG. 1

FIG. 2

FIG. 3

FIG. 4

FIG. 5

FIG. 6
